NOISE REDUCING ENCLOSURE FOR A COLD HEADER OR THE LIKE

Richard T. Wheeler, 20 Hemlock Drive,
Vernon, Conn. 06066

Filed Feb. 28, 1974, Ser. No. 446,814

Term of patent 14 years

Int. Cl. D6—99; D25—99

U.S. Cl. D25—16

FIG. 1

FIG. 2

FIG. 1 is a front, top and right side perspective view of a noise reducing enclosure for a cold header or the like showing my new design;

FIG. 2 is a rear, top and left side perspective view.

I claim:

The ornamental design for a noise reducing enclosure for a cold header or the like, as shown and described.
